UNITED STATES PATENT OFFICE.

JOSEPH B. CULLEN, OF MILWAUKEE, WISCONSIN.

MAIL-BOX.

1,151,666.

Specification of Letters Patent. Patented Aug. 31, 1915.

Application filed June 5, 1914. Serial No. 843,184.

To all whom it may concern:

Be it known that I, JOSEPH B. CULLEN, a citizen of the United States, and resident of Milwaukee, in the county of Milwaukee and State of Wisconsin, have invented new and useful Improvements in Mail-Boxes, of which the following is a description, reference being had to the accompanying drawings, which are a part of this specification.

10 The invention relates to mail boxes.

Formerly it has been the practice to construct mail boxes in which the mail is placed without regard to positioning it in the box in any special order, and when the box is 15 opened the mail is removed therefrom in disordered condition and placed in bags which are taken to the post office. After this, the mail is removed from the bags and placed in piles with the addresses face up, 20 in which condition it may be sorted.

To obviate the necessity of arranging the mail previous to its being sorted, is one of the objects of this invention.

With this end in view, the invention designs to provide a mail box in which the letters, when deposited therein with the addressed side face up, are arranged in a vertical stack, so that they may be removed in this condition, bound together, and carried 30 to the post office, where they may be readily sorted or run through the canceling machine.

The invention further designs to provide a mail box with a self-closing cover, and 35 means connected therewith to prevent pilfering of the contents of the box.

The invention further designs to provide a shelf upon which the mail may rest in a vertical stack, which shelf is automatically 40 operated by mechanism connected to the box coöperating with the stack of letters therein.

The invention further designs to provide a new and improved form of mail box.

In the drawings, Figure 1 is a vertical sectional view of the device. Fig. 2 is a vertical sectional view of the device. Fig. 3 is a front elevation, parts being broken away. Fig. 4 is a section taken on the line 4—4 of Fig. 1.

50 The device comprises a box having a base 10, back 11 and sides 12 and 13, the back and

the base projecting outwardly, to provide a space between the sides 12 and 13 and the outer edges of said back and base. Side covers 14 are designed to fit on the outer 55 edges of the back and base, forming a space between them and the sides 12 and 13. A top cover 15 is hinged to the upper end of the back 11 and is secured to the side covers 14 by rods 16, each secured at one end to the 60 cover 15, and detachably secured to the side covers 14 by means of brackets 17 having apertures therein through which the other ends of the rods pass, said ends being secured in position by wing nuts 18. The 65 front of the box is provided with a door 19 hinged to one of the sides, and which may be locked to the other.

The sides 12, 13 and 14 at the upper ends and adjacent the top cover, are recessed, 70 having a horizontally extending portion 20 and an upwardly inclined portion 21, a plate 22 resting upon the edges of the sides at the portion 20 and extending thereacross, and a plate 23 resting upon the edges of the 75 sides at the portion 21, and extending thereacross, said plate 23 having a transversely extending aperture or slot 24 adjacent its bottom edge for receiving the mail. A partition 20' is secured to the sides 12 and 13, 80 and forms the back of the mail box proper.

A cover 25 is pivotally secured to the box adjacent the slot 24 by pins 26 secured to it adjacent one edge, which pins are pivotally mounted in brackets 27 secured to the sides 85 12 and 13. Counterweights 28 are rigidly secured to the ends of the pin 26, as shown in Figs. 1 and 4, so that, when the cover 25 is turned down so as to rest upon the plate 22, the weights will assume the position 90 shown in dotted lines in Fig. 2, and on a release of the cover it will return to its normal position to cover the slot 24 and rest upon the plate 23. This construction thus serves to provide a self-closing cover. 95

The means for receiving and arranging the mail in the box in the form of a stack, comprises mechanism connected to and operated by the cover 25, which coöperates with an automatically adjustable support or shelf 100 hereinafter described.

The mechanism connected to and operated

by the cover comprises a movable rack 29 having rack bars 30, said rack carrying pins 31 which are pivotally connected to one of the ends of a pair of upwardly curved arms 32, the other ends of which are pivotally secured to pins 33 secured to the cover 25 adjacent the upper edge thereof. The arms 32, when moved by the movement of the cover 25, serve to move the rack backwardly 5 and forwardly, and to rotate the same, the rack being supported by the pins 31 which engage and are movable in longitudinally extending slots 34 in the sides 12 and 13, which slots also serve to limit the movement 10 of the rack. The partition 20' is provided with a plurality of vertical recesses or slots 35 in which the rack bars 30 are free to move, and a plurality of bars 36 are secured to the upper edge of the partition 20', and 15 extend outwardly therefrom to a position adjacent the plate 23, and are disposed adjacent the slots 35, thereby forming a plurality of horizontal slots which form a continuation of the vertical slots 35, so that the 20 rack bars 30 are free to move therein. The slots 35 in the partition 20' and the continuation of these slots between the bars 36 form a fixed rack within the box which 25 operates with the movable rack to uniformly deposit the mail in the form of a stack. Arms 36' are secured to the ends of the pins 31 and are operatively secured to arms 32 by springs 37, which permit movement of the rack with respect to the arms 32. An 30 inner cover plate 38 is slidably secured adjacent the plate 23 by a plurality of pins 39 on either side thereof, which move in slots 40 in the sides 12 and 13, and which are operatively connected with the curved arms 32, said arms being disposed between said 35 pins. This plate 38 has a slot 41 which registers with the slot 24 when the cover 25 is wide open.

The automatically adjustable shelf 45 comprises a shelf 42 fitting between the sides 12 and 13, and having its rear edge disposed adjacent the partition 20' of the box, which construction forms a chute open at its front end. The shelf has a depending portion 43 50 which carries lugs 44 slidably secured in vertical slots 45 in the sides of the box, and to which are connected one of a pair of flexible connections 46 which pass over pulleys 47 pivotally mounted upon the sides of the 55 box, and carry counterweights 48 at their other ends. Owing to this construction, there is a constant tendency for the shelf to move upwardly, but this is checked by an adjustable locking means comprising a pair of 60 ratchet bars 49 secured to said shelf by a pin and slot connection, the outer ends of said bars registering with a pair of toothed racks 50 secured to the sides 12 and 13, said bars being yieldingly pressed apart to engage the 65 racks 50 by a spring 51 interposed between

their inner ends. This construction serves to lock the shelf against upward movement by the counterweights, but permits downward movement, as the teeth on the rack have downwardly inclined sides 52 and horizontal sides 53. The open side of the chute is partially closed by a pair of spring controlled doors 54 hinged to the sides 12 and 13 of the box and secured in closed position by springs 55.

The partition 20', sides 12 and 13, doors 54 and adjustable shelf 42 form an extensible chute having an open space between the doors, so that the letters which are arranged therein in the form of a stack, may be taken 80 therefrom in this condition.

The operation of the device is as follows: The cover 25, shown in closed position in Fig. 1, is pulled down to open position, as shown in Fig. 2. In closed position, the 85 rack bars 30 are raised as shown in dotted lines in Fig. 1. The pins are at the farthest end of the slots 34, and the inner cover 38 in raised position, the pins 39 thereon being in their uppermost position in the slots 40. 90 As the cover 25 moves forwardly, the arms 32 move with it, carrying the rack 29, the pins 31 on the rack moving in the slots 34; the counterweights 28 move upwardly and the inner cover 38 moves downwardly, the 95 pins 39 thereon moving in the slots 40, which movement continues until the cover 25 reaches its extreme forward or open position, as shown in Fig. 2. This exposes the slot 24 in the plate 23 and the slot 41 in the 100 cover 38, and a letter is placed therein with the addressed side face up, suitable instructions being provided on the cover for this purpose. The letter deposited under these conditions rests upon the face of the rack 105 bars 30, which bars are disposed in the slots 35, so that the letter is between said bars and the bars 36. Then the cover is released, and under the action of the weights 28 is moved to closed position. During the first 110 part of this movement, the rack 29 is moved upwardly, and the letter carried by the bars 30 is forced upwardly against the bars 36, and being interposed between the bars 30 and 36, prevents further upward movement 115 of the rack bars which now, by reason of the spring connection with the arms 32, are moved longitudinally along the under face of the letter, until they are released therefrom and the letter drops down upon the 120 shelf 42. At the same time that the rack 29 and arms 32 are moving backwardly, the inner cover 38 is moving downwardly to cover the slot 24. Thus the movable rack 29 and the fixed rack formed by the bars 36 and partition 20' coöperate to form a means for automatically and uniformly depositing mail 125 in the box in the form of a stack.

The above operations take place in depositing each letter, and as the successive 130

letters fall upon the shelf 42, they are arranged in the form of a stack with their addressed sides up. As each letter takes its place upon the preceding letter in the stack, 5 it is held in this position by the letters beneath, and on the opening of the box the rack bars 30 will move over and press down upon the topmost letter of the stack, which downward movement will cause a downward 10 movement of the shelf 42 against the upward movement of the weights 48, and on the termination of the downward movement, the ratchet bars 49, which are free to move downwardly, as previously pointed out, will be forced in position under the sides 53 of 15 one of the teeth on the racks 50, and further upward movement of said shelf prevented. Thus it follows that as successive letters are deposited within the box, the shelf 42 moves 20 downwardly as the stack increases, until the chute is completely filled.

It will be noted that the chute is so shaped and the partition 20' so positioned that only mail which is inserted lengthwise of the slot 24 can be deposited so that the present construction insures a uniform stacking of the mail within the box.

The mailman, in collecting, opens the outer door 19, and, placing his hand between the spring hinged doors 54, grasps a quantity of letters and pulls them out, and binds them together in bundles.

It will be further noted that the inner cover 38 forms a guard means and prevents 35 any tampering with the contents of the box through the slot 24, for as soon as the cover is started on its upward movement, the cover 38 moves up to cover the slot 24.

The invention thus exemplifies a mail box 40 which is constructed so that mail may be deposited therein in the form of a stack, to facilitate its removal from the box and its future handling at the distributing office.

The invention is not to be restricted to the 45 details of construction herein set forth, but may be varied so as to be within the scope of the appended claims.

What I claim as my invention is:

1. In a mail box, the combination, with a 50 box body, of an extensible chute, means within said body for automatically and uniformly depositing mail on its flat sides in said chute in the form of a stack, and means for permitting of the removal of the mail 55 from the box in this form.

2. In a mail box, the combination, with a 60 box body, of a movable cover, and means within said body and operatively connected with said cover for automatically depositing mail in said body in the form of a stack.

3. In a mail box, the combination of a box 65 body having a mail receiving slot therein, a cover secured to said body adjacent said slot, and mechanism comprising means operatively connected with said cover for de-

positing the mail in the box in the form of a stack.

4. In a mail box, the combination of a box body having a mail receiving slot therein, a 70 cover pivotally secured to said body adjacent said slot, and mechanism comprising means operatively connected with said cover for depositing mail in the box in the form of a stack, and with one of its flat sides uppermost.

5. In a mail box, the combination of a box body having a mail receiving slot therein, a 80 cover pivotally secured to said body adjacent said slot, a chute for receiving the mail after it has passed through the slot, and mechanism comprising means connected to the cover and operated thereby for depositing the mail in the chute in the form of a stack.

6. In a mail box, the combination of a box 85 body having a mail receiving slot therein, a cover pivotally secured to said body adjacent said slot, a chute for receiving mail after it has passed through the slot, and means comprising a rack connected to the 90 cover and operated thereby for depositing the mail in the chute in the form of a stack.

7. In a mail box, the combination of a box body having a mail receiving slot therein, a 95 cover pivotally secured to said body adjacent said slot, a chute for receiving mail after it has passed through the slot, and means comprising a sliding and rotatable rack connected to the cover and operated thereby and a fixed rack for depositing the 100 mail in the chute in the form of a stack.

8. In a mail box, the combination of a box body, a chute in said body for receiving the 105 mail, means for depositing the mail in said chute in the form of a stack, and means for varying the length of said chute.

9. In a mail box, the combination of a box body, a chute in said body for receiving the 110 mail, means for depositing the mail in said chute in the form of a stack, and means for automatically varying the length of said chute.

10. In a mail box, the combination of a box body having a mail receiving slot therein, a cover pivotally secured to said body adjacent 115 said slot, a chute for receiving mail, mechanism comprising means connected to the cover and operated thereby for depositing the mail in the chute in the form of a stack, and means for varying the length of 120 said chute.

11. In a mail box, the combination of a box body having a mail receiving slot therein, a cover pivotally secured to said body adjacent 125 said slot, a chute for receiving the mail from said slot, mechanism comprising means connected to the cover and operated thereby for depositing the mail into the chute in the form of a stack, and an adjustable shelf for holding the mail so deposited. 130

12. In a mail box, the combination of a box body having a mail receiving slot therein, a cover pivoted to said body adjacent said slot, a chute for receiving mail from 5 said slot, said chute comprising sides and a back, and a pair of doors for partially enclosing the front of said chute, mechanism comprising means connected to the cover and operated thereby for depositing the 10 mail in said chute in the form of a stack, and an adjustable shelf for receiving the mail so deposited.

13. In a mail box, the combination, with a box body of an extensible chute, and means 15 for automatically depositing mail on its flat sides in said chute in the form of a stack.

14. A mail box comprising a box body, mechanism within said body for automatically depositing mail therein in the form of 20 a stack, and means for operating said mechanism, said mail being deposited with one of its flat faces uppermost.

15. In a mail box, the combination, with a box body, of means for receiving mail as defined 25 in the body, a movable mail-receiving support in said body, means coöperating with said receiving means to automatically deposit mail upon said movable support in the form of a stack, said receiving means also serving to secure the mail so stacked 30 upon said support.

16. A mail box comprising a box body, movable means within the body for receiving the mail thereon, means for reciprocating 35 said movable means and means coöperating with said movable means for automatically depositing the mail in said body in the form of a stack.

17. A mail box comprising a box body, 40 movable means within said body for receiving the mail on one of its flat sides, means for reciprocating said movable means, and means coöperating with said movable means for automatically depositing the mail in said body in the form of a stack.

18. A mail box comprising a box body, 45 fixed means within said body, movable means within the body for receiving the mail thereon, and means for operating said movable means, said movable means and fixed means coöperating to automatically deposit the mail in said body in the form of a stack.

19. A mail box comprising a box body, 50 fixed means within said body, movable means within the body for receiving mail thereon, said mail being interposed between the fixed and movable means, and means for reciprocating and rotating the movable means to move the mail against the fixed means and 55 deposit it in the form of a stack.

20. A mail box comprising a box body, 60 movable means within the body for receiving mail thereon, fixed means within said body, and means for reciprocating and oscil-

lating said movable means, comprising an 65 arm connected to the movable means, a lever pivotally connected to said arm, said movable and fixed means coöperating to automatically deposit the mail in said body in the form of a stack. 70

21. A mail box comprising a box body, movable means in the body for receiving mail thereon, fixed means within said body, and means for reciprocating and oscillating 75 said movable means, comprising an arm connected to the movable means, a weighted lever pivotally connected to said arm, said movable and fixed means coöperating to automatically deposit the mail in said body in the form of a stack. 80

22. A mail box comprising a box body having a mail receiving slot therein, means in said body for receiving and automatically depositing mail therein in the form of a 85 stack, means for operating said means, and guard means for the slot operated by said operating means. 90

23. A mail box comprising a box body having a mail receiving slot therein, means in said body for receiving and depositing 95 mail therein in the form of a stack, means for operating said means, and a guard means for the slot comprising a plate slidably mounted in said body and operated by said operating means. 95

24. In a mail box the combination of a box body, a chute in said body, means for depositing the mail in said chute, and means for automatically varying the length of said chute. 100

25. A mail box comprising a box body, an open-sided chute in said body, means for depositing the mail in said chute in the form of a stack, means for automatically varying the length of said chute, and movable means 105 for partially closing the open side of said chute.

26. A mail box comprising a box body, an open-sided chute in said body, means in said body for depositing mail in said chute 110 in the form of a stack, means for automatically varying the length of said chute, and self closing doors for partially closing the open side of said chute.

27. A mail box comprising a box body, 115 mechanism within said body for depositing the mail therein in the form of a stack, and automatically movable means for supporting the mail so deposited.

28. A mail box comprising a box body, 120 an open-sided chute in said body, means for depositing the mail in said chute in the form of a stack, means for automatically varying the length of said chute, and means for partially closing the open side of said chute. 125

29. A mail box comprising a box body, a movable support in said body, movable means for receiving and automatically de-

positing the mail in said body upon said support and for securing the mail so stacked between it and the support, and means for automatically moving said support to accommodate the increase of mail in the stack.

30. A mail box comprising a box body, a support in said body, means in said body for receiving and automatically depositing mail in said body upon said support in the form of a stack, and means for automatically moving said support downwardly as the stack increases comprising releasable means in engagement with said body.

31. A mail box comprising a box body, a support in said body, means in said body for receiving and automatically depositing mail therein in the form of a stack, means for releasably securing said support to the body to permit the support to move downwardly as the stack increases, and means for counteracting said downward movement to hold the mail between the support and the depositing means.

32. A mail box comprising a box body, a movable support in said body, guide means for said support, means for releasably securing said support to the body to permit said support to move downwardly in said guides and lock it against upward movement, and means in said body for receiving and automatically depositing mail therein upon said support in the form of a stack.

33. In a mail box, the combination of a box body, a movable support in said body, a plurality of racks in said body, ratchet bars secured to said support and releasably engaging said racks, and means in said body for receiving and automatically depositing mail therein upon said support in the form of a stack.

34. A mail box comprising a box body, a support in said body, means in said body for receiving and automatically depositing mail therein in the form of a stack, means for releasably securing said support to the body to permit said support to move downwardly and lock it against upward movement, and means for counteracting said downward movement to hold the mail between the support and the depositing means.

35. A mail box comprising a box body, a support in said body, means in said body for receiving and automatically depositing mail therein in the form of a stack, means for releasably securing said support to the body to permit said support to move downwardly and lock it against upward movement, and gravity actuated means for counteracting said downward movement to hold the mail between the support and the depositing means.

36. A mail box comprising a box having a mail receiving slot therein, a self-closing cover secured to said body adjacent said

slot, and mechanism comprising means operatively connected with said cover for depositing the mail in the box in the form of a stack.

37. In a mail box, the combination of a box body having a mail receiving slot therein, a self-closing cover pivotally secured to said body adjacent said slot, and mechanism comprising means operatively connected with said cover for depositing mail in the box in the form of a stack, and with one of its flat sides uppermost.

38. In a mail box, the combination of a box body having a mail receiving slot therein, a self closing cover pivotally secured to said body adjacent said slot, a chute for receiving the mail after it has passed through the slot, and mechanism comprising means connected to the cover and operated thereby for depositing the mail in the chute in the form of a stack.

39. In a mail box, the combination of a box body having a mail receiving slot therein, a self-closing cover pivotally secured to said body adjacent said slot, a chute for receiving mail after it has passed through the slot, and means comprising a rack connected to the cover and operated thereby for depositing the mail in the chute in the form of a stack.

40. In a mail box, the combination of a box body having a mail receiving slot therein, a self-closing cover pivotally secured to said body adjacent said slot, a chute for receiving mail after it has passed through the slot, and means comprising a sliding and oscillating rack connected to the cover and operated thereby and a fixed rack for depositing the mail in the chute in the form of a stack.

41. In a mail box, the combination of a box body having a mail receiving slot therein, a self closing cover pivotally secured to said body adjacent said slot, a chute for receiving mail, mechanism comprising means connected to the cover and operated thereby for depositing the mail in the chute in the form of a stack, and means for varying the length of said chute.

42. In a mail box, the combination of a box body having a mail receiving slot therein, a self-closing cover pivotally secured to said body adjacent said slot, a chute for receiving the mail from said slot, mechanism comprising means connected to the cover and operated thereby for depositing the mail into the chute in the form of a stack, and an automatically adjustable shelf for holding the mail so deposited.

43. In a mail box, the combination of a box body having a mail receiving slot therein, a self-closing cover pivoted to said body adjacent said slot, a chute for receiving mail from said slot, said chute comprising sides

6
and a back, and a pair of doors for partially inclosing the front of said chute, mechanism comprising means connected to the cover and operated thereby for depositing the mail in said chute in the form of a stack, and an automatically adjustable shelf for receiving the mail so deposited.

Copies of this patent may be obtained for five cents each, by addressing the "Commissioner of Patents, Washington, D. C."

In testimony whereof, I affix my signature, in presence of two witnesses.

JOSEPH B. CULLEN.
